UNITED STATES PATENT OFFICE.

FRANKLIN L. BARBER AND CHARLES S. WALTON, OF CHICAGO, ILLINOIS, ASSIGNEES
TO STANDARD CAR TRUCK COMPANY, OF CHICAGO, ILLINOIS, A CORPORATION OF
NEW JERSEY.

CAR-TRUCK.

1,229,398.

Specification of Letters Patent. Patented June 12, 1917.

Application filed April 28, 1917. Serial No. 165,077.

To all whom it may concern:

Be it known that we, FRANKLIN L. BARBER and CHARLES S. WALTON, citizens of the United States, residing at Chicago, in the county of Cook and State of Illinois, have invented certain new and useful Improvements in Car-Trucks; and we do hereby declare the following to be a full, clear, and exact description of the invention, such as will enable others skilled in the art to which it appertains to make and use the same.

Our invention relates to improvements in car trucks, and particularly to six-wheeled equalized freight car trucks. To the above end, generally stated, the invention consists of the novel devices and combinations of devices hereinafter described and defined in the claims.

In the accompanying drawings, which illustrate the invention, like characters indicate like parts throughout the several views.

Referring to the drawings,

Figure 1 is a fragmentary plan view of the improved car truck;

Fig. 2 is a side elevation of the same, with some parts broken away and some parts sectioned;

Fig. 3 is a transverse vertical section taken on the irregular line 3-3 of Fig. 1;

Fig. 4 is a detail view in vertical section taken on the line 4-4 of Fig. 2; and

Fig. 5 is a detail view in section taken on the line 5-5 of Fig. 2.

Each side frame of the improved car truck is indicated by the numeral 6 and, as shown, is of cast steel with a general cross section in the form of a box, the walls of which are suitably reinforced. It is, of course, understood that the side frames may be made from structural steel. The bottom of each side frame 6 is cut away at 7 to afford openings for journal boxes which are mounted between pedestals 9, with freedom for vertical movement. The pedestals 9, as shown, are formed separate from the side frames 6, have a greater transverse width than said side frames, and their upper ends are bifurcated to receive said side frames and are detachably secured thereto by short nut-equipped bolts 10. The lower ends of each pair of pedestals 9 are rigidly connected, below the respective journal box 8, by a tie bar 11 secured thereto by bolts 12. To further assist in rigidly connecting the

tie bars 11 to the pedestals 9, the ends thereof are bent upward to engage the backs of said pedestals. The wheels and axles of the improved truck are indicated by the numerals 13 and 14, respectively.

Between each pair of wheels 13, the side frame 6 is dropped and has formed therein a bolster opening 15. The side frame 6, at the sides of the bolster openings 15, is constructed to form bolster columns 16. These bolster columns 16 extend from the bottoms of the bolster openings 15 to the top of the side frame 6 and, throughout substantially the full height of said openings, have a greater width than the transverse width of said side frame. In the top of the side frames 6, at each end thereof, is formed a spring-cap 17. Openings are formed in the side frames 6 to permit casting thereof, for the sake of lightness and to permit the assembling of certain of the parts of the truck located within the side frames.

Pairs of angle cross-ties 18 are rigidly connected to the drop portions of the side frames 6 and the ends thereof extend in the bolster openings 15 and are secured by rivets to said side frames. The vertical flanges of the cross-ties 18 extend upward and the horizontal flanges thereof are turned toward each other and brought into close engagement, except at their ends where they are spread to bring said vertical flanges into engagement with the inner wearing surfaces of the bolster columns 16 and their horizontal flanges into seats formed in the side frames 6, at the bottoms of the bolster openings 15.

The truck bolster 19 is of the double type and, as shown, is cast in one piece with its four ends projecting into the bolster openings 15. Side bearing brackets 20 are integrally cast with the bolster 19 and are protected by steel shoes 21. The lower member of a center bearing 22 is also cast integral with the bolster 19. Brake hangers 23 are riveted to the inner faces of the side frames 6. Spring-caps 24 are supported on coiled bolster springs 25 arranged in groups of four and seated on the side frames 6, at the bottoms of the bolster openings 15. The ends of the spring-caps 24 are notched in the customary manner to receive the bolster columns 16, which act as guides therefor. The ends of the bolster 19 are supported on the

spring-caps 24 by lateral motion rollers 26 mounted in contours 27 formed in the under side of said bolster and in the tops of said spring-caps.

5 Intermediately fulcrumed on each journal box 8, is a cast equalizing lever or bar 28 having on its lower face a fulcrum lug 29 mounted in a bearing seat 30 on the respective journal box 8 and supports said lever for rocking movement transversely of said journal box. These equalizing levers 28 are located within the side frames 6 and have formed in their upper surfaces and at the ends thereof concave seats 31. Supported on 10 the outer ends of the outer equalizing levers 28, directly below the spring-caps 17, are spring-bases 32, having on their under sides segmental bearing lugs 33 mounted in the respective seats 31 and which permit the 15 required rocking movements of said levers. Also cast with the spring-bases 32, at the ends of the bearing lugs 33, are flanges 34 which 20 embrace said levers and thereby hold the spring-bases against transverse movement 25 thereon. Interposed between each spring-base 32 and the overlying spring-cap 17, is a yielding abutment, in the form of two coiled springs 35, spaced, one in advance of the other, longitudinally of the respective 30 equalizing lever 28.

The inner ends of the outer equalizing levers 28 are connected to the ends of the intermediate equalizing lever 28 of each side frame 6 by pairs of bell-crank levers 36 and 35 compression members, in the form of coiled springs 37. Each bell-crank lever 36 has on its sides segmental bearings 38, which are mounted on short axially alined trunnions 39 cast integral with the inner vertical walls 40 of the side frames 6. The short horizontal arms of the bell-crank levers 36 extend under the adjacent ends of the equalizing levers 28 and are connected thereto by rectangular links 40, through which said bell-crank levers 45 and equalizing levers project. The upper transverse portions of the links 40 are made convex to fit the seats 31 and the lower transverse portions thereof are also formed convex to fit concave seats 41 formed 50 on the under side of the short arms of the bell-crank levers 36.

The long arms of the bell-crank levers 36 extend vertically upward and terminate in bearing heads 42, which extend into socket-like bearings 43 formed in the outer ends 55 of horizontally disposed and axially alined plungers 44. These plungers 44 are mounted in bearings 45 formed in the upper portions of the bolster columns 16, for endwise sliding movement longitudinally, with respect to the equalizing levers 28. The inner ends 60 of the plungers 44 project into the bolster openings 15 and have integrally formed therewith spring-caps 46, between which the 65 compression springs 37 are compressed.

Bosses 47, on the spring-caps 46, extend into the springs 37 and support the same from said spring-caps. By reference to Fig. 3, it will be noted that the ends of the bolster 19 are beveled to clear the compression springs 70 37. It is also important to note that the bolster springs 25, abutment springs 35 and compression springs 37 are of one size and shape, thus making the same interchangeable, which assists materially in assembling 75 the improved truck and in replacing springs, in case they are broken or worn out.

From the above description, it is evident that the load of the car is direct on the double bolster 19 and it, in turn, is supported 80 from the side frames through the bolster springs 25 and lateral motion rollers 26. The weight on the side frames is distributed on the journal boxes 8 through the equalizing levers 28, bell-crank levers 36 and compression springs 37. It is also evident that each 85 wheel of a car truck is allowed to move vertically, independent of the other thereof.

What we claim is:—

1. In a car truck, the combination with 90 side frames and journal boxes, of equalizing levers intermediately fulcrumed on the journal boxes, abutments between the outer ends of the equalizing levers and side frames, bell-crank levers having one of their 95 arms connected to the inner ends of said equalizing levers, and compression springs interposed between the other arms of the bell-crank levers.

2. In a car truck, the combination with 100 side frames and journal boxes, of equalizing levers intermediately fulcrumed on the journal boxes, springs affording abutments interposed between the outer ends of the 105 equalizing levers and side frames, bell-crank levers having one of their arms connected to the inner ends of said equalizing levers, and compression springs interposed between the other arms of the bell-crank levers.

3. In a car truck, the combination with 110 side frames and journal boxes, of equalizing levers intermediately fulcrumed on the journal boxes, abutments between the outer ends of the equalizing levers and side frames, bell-crank levers, links connecting one of the arms of the bell-crank levers with the inner ends of the equalizing levers, and compression springs interposed between the other arms of said bell-crank levers.

4. In a car truck, the combination with 115 side frames and journal boxes, of equalizing levers intermediately fulcrumed on the journal boxes, abutments between the outer ends of the equalizing levers and side frames, bell-crank levers having one of their 125 arms connected to the inner ends of the equalizing levers, plungers mounted in seats in the side frames and with the outer ends of which the other arms of the bell-crank 130

- levers engage, said plungers having spring-caps on their inner ends, and compression springs interposed between said plungers and seated on the spring-caps thereof.

5 5. In a car truck, the combination with side frames and journal boxes, of equalizing levers intermediately fulcrumed on the journal boxes, abutments between the outer ends of the equalizing levers and side frames, bell-crank levers having one of their arms connected to the inner ends of the equalizing levers, plungers mounted in seats in the side frames and having in their outer ends sockets in which the other arms of the bell-crank levers are seated, said plungers having spring-caps on their inner ends, and compression springs interposed between said plungers and seated on the spring-caps thereof.

10 6. In a car truck, the combination with side frames and journal boxes, of equalizing levers intermediately fulcrumed on the journal boxes, springs affording abutments between the outer ends of the equalizing levers and side frames, bell-crank levers having one of their arms connected to the inner ends of the equalizing levers, and compression springs interposed between the other arms of the bell-crank levers, said abutment, compression and bolster springs being interchangeable.

15 7. In a car truck, the combination with side frames having bolster openings, journal boxes, a bolster having its ends extending into said bolster openings, and springs supporting the bolster from the side frames, of equalizing levers intermediately fulcrumed on the journal boxes, abutments between the outer ends of the equalizing levers and side frames, bell-crank levers having one of their arms connected to the inner ends of the equalizing levers, and compression springs interposed between the other arms of the bell-crank levers, said compression and abutment springs being interchangeable.

20 8. In a car truck, the combination with side frames, journal boxes, bolster, and springs supporting said bolster from the side frames, of equalizing levers intermediately fulcrumed on the journal boxes, springs affording abutments between the outer ends of the equalizing levers and side frames, bell-crank levers having one of their arms connected to the inner ends of the equalizing levers, and compression springs interposed between the other arms of the bell-crank levers, said abutment, compression and bolster springs being interchangeable.

25 9. In a car truck, the combination with side frames having bolster openings, journal boxes, a bolster having its ends extending into said bolster openings, and springs supporting the bolster from the side frames, of equalizing levers intermediately fulcrumed on the journal boxes, abutments between the outer ends of the equalizing levers and side frames, bell-crank levers having one of their arms connected to the inner ends of the equalizing levers, plungers mounted in seats in the side frames and with the outer ends of which the other arms of the bell-crank levers engage, said plungers having spring-caps on their inner ends which extend into the bolster openings above the bolster, and compression springs interposed between said plungers and seated on the spring-caps thereof.

30 10. In a car truck, the combination with side frames, journal boxes, bolster, and springs supporting said bolster from the side frames, of equalizing levers intermediately fulcrumed on the journal boxes, abutments between the outer ends of the equalizing levers and side frames, bell-crank levers having one of their arms connected to the inner ends of the equalizing levers, and compression springs interposed between the other arms of the bell-crank levers, said
